UNITED STATES PATENT OFFICE.

ARTHUR H. DODGE, OF NEW YORK, N. Y., ASSIGNOR TO THE J. G. WILSON CORPORATION, OF NEW YORK, N. Y., A CORPORATION OF VIRGINIA.

DOOR CONSTRUCTION.

Application filed December 17, 1923. Serial No. 681,173.

To all whom it may concern:

Be it known that I, ARTHUR H. DODGE, a citizen of the United States, residing at New York, county of New York, State of New York, have invented a certain new and useful Improvement in Door Constructions, of which the following is a clear, full, and exact description.

This invention relates to door construction and particularly to strips for closing the space between the lower edges of the doors of a folding partition and the floor. However soundproof the body of a door may be made, sound will pass to a considerable extent through the space between the lower edge of the door and the bottom of the door frame unless adequate provision is made to prevent it. Failure to make such provision is an especial drawback in the case of movable partitions used to subdivide temporarily a large room into small rooms, and may in some instances render such partitions practically useless. Folding partitions should be easy to move from open to closed position, and should not require special skill or attention in operation.

The main object of this invention is to provide strips which may be attached to the doors making up a folding partition, which strips will automatically close the space between the bottoms of the doors and the floor when the partition is unfolded to close the door frame, but which will not interfere with free movement of the sections of the partition between open and closed position.

Doors making up a folding partition should be free to slide until they are moved into their fully closed position; swinging doors should likewise be free to swing until they are closed. Another important object of the invention is to provide a sound insulating strip arranged to close automatically the space between the lower edge of the door and the floor when the door is closed, which may be applied to any type of folding or swinging door and is constructed to permit free movement of the door until it is fully closed.

Another object is to provide door strip mechanism of the character above described, which will be simple and economical to construct and apply to the doors of a folding

partition and which will be entirely automatic in operation.

Still another object is the provision of positively acting operating mechanism for door strips requiring a minimum expenditure of energy to operate, and constructed to save wear on the parts so that it may last as long in use as the other elements of the door of which it forms a part.

One example of the invention as applied to a folding partition is illustrated in the drawings, in which:

Fig. 1 is a front elevation of a typical partition made up of three pairs of hinged doors provided with the improved strip, shown in fully closed position;

Fig. 2 is a section on the line 2—2 of Fig. 1, but with the partition partially open;

Fig. 3 is a front elevation, with parts broken away, showing the strip mechanism applied to the left-hand end door of the partition illustrated in Fig. 1;

Fig. 4 is a horizontal section on the line 4—4 of Fig. 3;

Figs. 5 and 6 are vertical sections on the lines 5—5 and 6—6, respectively, of Fig. 3, showing the strip and its attachment to the lower edge of the door;

Fig. 7 is a front elevation with parts broken away, of the strip applied to a partition door containing a shuttle door, as the door next the left-hand end in Fig. 1;

Fig. 8 is a horizontal section on the line 8—8 of Fig. 7 showing a preferred strip operating mechanism for shuttle doors, with the main door and shuttle door both closed;

Fig. 9 is a view of the parts shown in Fig. 8 but with the main door closed and the shuttle door open;

Fig. 10 is a view of the parts shown in Fig. 8 but with the main door open and the shuttle door shut;

Fig. 11 is a view similar to Fig. 8 of a modification;

Fig. 12 is a front elevation of a strip applied to an intermediate pair of doors, such as the two middle doors shown in Fig. 1, the doors being in fully closed position and the strip operated;

Fig. 13 is a view of the parts shown in Fig. 12 but with the doors out of closed position and the strip raised from the floor;

Fig. 14 is a horizontal section on the line 14—14 of Fig. 12;

Fig. 15 is a horizontal section on the line 15—15 of Fig. 12;

Fig. 16 is a view similar to Fig. 15 showing a modification;

Fig. 17 is a front elevation of a strip applied to the pivoted doors shown at the right end of Fig. 1, the doors being closed and the strip operated;

Fig. 18 is a section on the line 18—18 of Fig. 17 with the doors partly open;

Fig. 19 is a vertical cross section similar to Fig. 5 showing a modification;

Fig. 20 is a fragmentary horizontal section of a strip applied to a single swinging door with a stationary jamb;

Fig. 21 is a vertical section on the line 21—21 of Fig. 20;

Fig. 22 is a perspective of a detail shown in Figs. 20 and 21; and

Fig. 23 is a fragmentary horizontal section of a modified construction for use with a swinging door and a stationary jamb.

Figs. 3, 7, 12 and 17 when aligned from left to right, in the order named, show mechanism for operating all the door strips of a partition such as illustrated in Figs. 1 and 2.

Partitions of the type shown in Fig. 1 are made up of any number of pairs of doors needed to close the open doorway or frame, three such pairs 24, 25—26, 27—28, 29 being shown in the present instance. The alternate doors 24, 26 and 28 are connected as by the invisible hinges 30 to the adjacent doors 25, 27 or 29, as the case may be, to form a folding section or unit of the partition. When the doorway is open, the units are all folded

compactly together next to the fixed door jamb 31, shown at the right in Figs. 1, 2 and 17. To close the doorway, the first unit is unfolded and straightened out to the position illustrated by doors 24, 25 in Fig. 2, the remaining units are then unfolded and caused to slide across the open frame until when the last unit has been partially unfolded, the doorway will be substantially closed, the leading edge of the first door 24 being in light contact with the jamb 32 and the upright edges of each unit being closed to or in contact with the edges of the adjacent units. The last door 29 of the unit next to the jamb 31, against which the doors

fold when open, is pivoted on the pins 33, so that doors 28 and 29 in being straightened out act as a toggle lever to force all the other doors tightly together and against the jamb 32. This jamb 32 is yieldingly mounted on springs 34 to compensate for any irregularities in the width of the doors caused by faulty construction, changes in temperature, etc.

The doors selected to illustrate the in-

vention are supported on castors 35 and are guided in their movement by plates or pins 36 at the lower outside corners of each unit, which engage a grooved track 37 set in flush with the floor. Suitable anti-friction guides may be provided at the upper corners of the door units to guide the doors in an overhead track, not shown. Whether the doors are supported as described or are hung from above, and whether the partition is of the folding, accordion, or parallel track type, the edges of the doors will close tightly together when the partition is in position to close the door frame, so that the present invention which provides a door strip operable in response to relative movement of the door edges is applicable to any type of folding partition. In the construction selected for illustration, the first section of the partition, consisting of doors 24, 25 has been shown provided with a wicket or shuttle door 38 hinged to the jamb section 39 of door 25 to swing towards and from jamb section 40 and thus permit passage through the partition when in closed position shown in Fig. 1. It will become apparent, however, that any desired number of shuttle doors may be provided and located in any convenient sections of the partition without changing the operation of the strip.

The castors 35 and guide plates or pins 36 are mounted in suitably cut away portions at the opposite lower corners of the partition units, and are enclosed by the cover plates which have been designated as A, B and C on the respective doors 24, 25—26, 27—28, to aid in matching up Figs. 3, 7, 12 and 17 as an assembly of the whole partition.

The door strip and actuating mechanism applied to the end door 24 are typical and will be described in detail, only the differences necessitated by different operating conditions being pointed out in connection with the strip mechanism on the other doors of the partition. Preferably the sound retarding strip is assembled as a unit in the sheet metal housing 41 which is formed as a deep channel (Fig. 5) having a back wall 42 and a front wall 43. The housing is secured to the face of the door near its lower edge by a number of screws 44.

The base of the strip proper is a much smaller channel 45, the downturned edges of which grip and retain the strip 46 (Fig. 6). The strip may be made of rubber, leather, or any suitable textile fabric, and is formed where it contacts with the frame or floor 47 into a bead 48 which is stuffed with suitable fibre 49, such as rope yarn. The base 45 is mounted for vertical movement relative to the housing and thus towards and away from the floor by pins 50

which pass through vertical slots 51 and may be riveted to the back wall 42 of the housing. To actuate the strip in its vertical movement, there is provided a bar 52 extending parallel to the base 45 of the door strip and secured for longitudinal, horizontal movement to the rear wall 42 of the housing. This may be conveniently accomplished by slotting the actuating bar, as at 10 53, and riveting guide pins 54 which extend through the slots into the rear wall 42. The actuating member and the base are connected by suitable linkage, such as the strips 55, which are pivotally secured to the bar 52 and base 45 by pins 56. The strip is held in its normal position removed from the floor (Fig. 13) as by one or more springs 57, suitably secured between the actuating bar 52 and the housing as by a catch 58 on 15 the bar and pin 59 in the housing. Preferably the bar 52 is of the same length as the housing so as to be completely covered up out of sight when in its normal position. The ends of the bar are bent over at approximately right angles towards the door to form the abutments 60.

As the first section of the partition is unfolded to its straight position and slides along the track 37 to its closed position, obviously the strip will be out of contact with the frame so as to permit free movement of the door on its castors 35 or other supports. When the leading edge of door 24 reaches yielding jamb 32, the section made up of doors 24 and 25 is in its fully closed position and the door strip may be operated at this time, if desired. To operate the door strip when the door is forced against the jamb, there is provided a suitable abutment 61 which may be secured to the jamb, as by the screws 62, in position to strike the bent-over end 60 of the actuating bar. When the door is forced tightly against the jamb, the pressure of abutment 61 on the actuating bar 52 forces it to the right and thereby moves the upper ends of the links 55 to the right, the base 45 of the door strip being held against longitudinal movement by the guide pins 50 must therefore travel 40 downward until its bead 48 is pressed tightly against the floor or other bottom member of the door frame. The yielding flexible nature of the strip insures a tight connection at all points between the door strip and the floor, regardless of inequality in the distance from the lower edge of the door to the floor. In order to allow for accidental irregularities in the length of the abutment members, the operating links are 50 designed to occupy very nearly a vertical position when the strip is pressed against the floor, in which position the left-hand ends of the horizontal slots 53 in the actuating member have not yet reached the

guide pins 54. If the abutment 61 should be a little too long, the only result would be to force the upper ends of the links a little beyond their normal vertical operated position, but owing to the flexibility of the strip and the fact that considerable horizontal movement of the actuating bar produces but a very small vertical movement of the strip base when the links are nearly vertical, it will be obvious that the strip would make a good contact with the floor in 10 spite of such variation in the length of the abutment. Under certain circumstances it may be desirable to allow the left-hand end of the actuating bar to project beyond the edge of the housing when in its normal position, in which case the abutment may be either shorter than shown in Figs. 3 and 4, or it may be flush with the remaining surface of the yielding jamb, the amount which the abutment projects from the surface 15 against which the vertical edge of the door contacts being governed by the extent to which the actuating bar normally projects from the housing. It is considered most desirable, however, to have the moving parts 20 completely contained within the housing and to permit the stationary abutment to project the required distance to operate the door strip. 25

The door strip attached to the jamb portion 40 of door 25 is substantially identical in construction with that attached to the lower edge of door 24, and will be operated simultaneously with the strip on door 24 by the pressure of the right-hand end 60 30 of the actuating bar 52 against the left-hand end of the similar bar which operates the strip on jamb section 40. The projection of strip 52 on door 24 into jamb 40 can only take place when the doors are in 35 their straight and fully closed position, so there is no danger of breaking any of the parts during the folding movement of the doors which can only occur when the doors are at the extreme right-hand end of the 40 frame in position to be folded together. If only standard solid doors were used in making up the partition, the strip on each door could be operated by engagement with the actuating bar carried on the preceding door, 45 so that one abutment projecting from the jamb would move every actuating bar, but where shuttle doors are provided, as shown in connection with door 25, a somewhat different construction is necessary. 50

When the partition section containing the shuttle door has reached the limit of travel relative to the frame, and the shuttle door is closed relative to the jamb sections of the partition door of which it forms a part, 55 the door strip on the shuttle door must be in its operated position in engagement with the floor. The shuttle door strip must be

immediately raised from the floor whenever the shuttle door is swung on its hinges, and the closing of the shuttle door must not operate its door strip unless the entire section is in its closed position, since otherwise the shuttle door strip would prevent sliding movement of the partition section containing it unless the shuttle door were slightly open.

- 10 This invention satisfactorily meets these operating requirements by the construction shown in Figs. 7, 8, 9 and 10. The shuttle door 38 is provided with a door strip and actuating mechanism substantially the same as that described in connection with door 24, with the exception that the left-hand end of the bar 52 is held by spring 57 in contact with a yielding strip 63, here illustrated as a spring secured at one end to the edge of the shuttle door by the screws 64. It will be obvious, however, that a hinge member might be substituted for the spring member, if desired. The right-hand end of actuating bar 52 of jamb section 40 carries a bracket 65 in which there is journalled for rotation about a vertical axis a roller 66. When the partition section is in its fully closed position and the shuttle door 38 is closed, the actuating bar 52 on jamb section 40 will have been moved to the right so as to press spring member 63 against the actuating bar on the shuttle door and thus operate the door strip on said shuttle door. If the door is then swung to the position shown in Fig. 9, roller 66 rides off the yielding strip 63 so that spring 57 may move the actuating strip 52 to the left to lift the strip 45 and permit free swinging movement of the shuttle door. Conversely, closing movement of the shuttle door causes roller 66 to compress the member 63 against the edge of the door and again operate the shuttle door strip. In Fig. 10 the parts are shown in the positions occupied during the opening or closing of the partition as a whole. Owing to the fact that the left-hand door has not been moved up tightly against the yielding jamb, the actuating bar 52 and its roller 66 occupy their normal position, in which the roller is out of the path of movement of the yielding strip 63, so that even though the shuttle door 38 is closed against its jamb 40, the strip on the shuttle door will remain in its normal position raised from the floor.

An alternative construction is shown in Fig. 11, in which the bar 52 of section 40 is bent in the triangular shape indicated, so as to provide the sloping face 67 to serve as an abutment for the end of bar 52 on the shuttle door. To lessen friction between the bar 52 and the abutment 67, there is preferably provided a small roller 68 which may be rotatably secured to the end of bar

52 by bending said end to form an eye to receive the spindle carrying roller 68. The operating characteristics of this construction are exactly the same as that employing the larger roller and yielding strip. In either case, the jamb section 40 preferably has an extension 69 projecting somewhat beyond the dividing line between the shuttle door and the jamb, so as to protect the roller 66 or end 67 of the operating rod when the shuttle door is open. The rear wall 42 of the housing channel is slotted at 70 to allow for the passage of the bent end of the actuating bar.

The jamb section 39 to which the shuttle door is hinged, also carries its own section of door strip, but since the operation of the strip for this section should be independent of the open or closed position of the shuttle door, the strip is preferably operated in response to pressure from the next succeeding door 26 of the partition rather than from the preceding door which is the usual case. This jamb section 39 has the strip member 45, actuator 52, and spring 57, as in the previously described construction, but the spring 57 extends in the opposite direction so as normally to project bar 52 to the right somewhat beyond the right-hand edge of the jamb. An angle bracket 71 secured to the leading edge of door 26 projects slightly in advance of said edge, so that as the door comes into contact with door 25, bracket 71 abuts the end 60 of the actuating bar 52 of jamb section 39, thereby forcing it to the left and operating the links 55 to lower the strip against the floor, into the position shown in Figs. 7, 12 and 15. As in the case of all the other abutments which operate the door strips, the bracket 71 might be flush with the edge of door 26, in which case the bar 52 on jamb 39 would have to project farther beyond the vertical edge of the jamb, or the bracket 71 might project farther beyond the edge of its door, in which case the actuator on jamb 39 would not need to project beyond the edge of the jamb. In other words, any relative position of the end of the bar and the bracket which provides for sufficient longitudinal movement of the actuating bar to move the door strip may be used.

The door strip and its operating mechanism used on the standard intermediate partition section made up of doors 26 and 27, is substantially identical in construction and operation with that applied to door 24 and previously described. The only difference is that the right-hand end of bar 52 on door 27 need not have a bent-over face 60 since the next standard section is operated by an abutment plate 61 similar in all respects to that secured to the yielding jamb 32, which will engage the strip actuating bar 52 on the

next door. An abutment, such as the bracket 72 shown in Figs. 12 and 15, may be secured to the edge of the preceding door and the end 73 of bar 52 may be made somewhat longer than in the usual construction so as to strike the abutment bracket 72 as the door 26 is moved up against the jamb 39 of the preceding door 25. The particular construction of bracket 72 is not important, a chan-
nel-shaped bracket 72' being illustrated in Fig. 16 to perform the same function. The relative position of the ends 60 of the actuating bars 52 at one of the hinged joints, for example, between doors 26 and 27 is shown in Fig. 14, in full lines to indicate the strip-down position and in dot-dash lines showing the normal position when the strip is up from the floor. The last section of a partition made up of the pivoted door 29 and the door 28 fitted thereto, also have door strips of the same construction as those described, the sole difference being that instead of strips for the two doors being operated, either from a preceding or a follow-
ing unit of the partition, each of the actuating bars serves as the operating abutment for the other one, the ends 74 being curved as shown in Fig. 18. The reason for this operating arrangement is that the doors are in their fully closed position as soon as they have been straightened out. A sliding movement cannot, therefore, be used to operate the door strips. As the doors are pushed from their folded position, shown in Fig. 2, the toe portions of the bar ends 74 inter-engage and start to push apart the operating bars 52, but the curvature of the portions 74 is so arranged that the door strips will not be brought into firm contact with the floor until the doors are snapped into their fully straightened out position.

From the foregoing description it will be apparent that as the various partition sections are straightened out and moved across the frame to close the partition, no operation of the door strips will take place until the various sections are forced tightly together, since the various abutments will merely rest lightly against the respective ends of the actuating bars until the pressure between the doors is sufficient to overcome the force of springs 57, tending to hold the apparatus in its normal position. The pivoted doors 28, 29 in being straightened out, act as a toggle lever to force all the preceding sections together and against the spring jamb 32, so that under normal operating conditions all the door strips are moved into their closed position simultaneously as the pivoted doors are straightened out. It will be obvious that as many intermediate sections made up of doors hinged together identical with the doors 26, 27 may be interposed between the first unit and the pivoted doors as are required to fully close the door frame, how-

ever large; also the shuttle door sections may be placed in any relative position desired, the only difference being that the edge of the door following after a shuttle door section should be equipped with a bracket 71 to operate the hinge carrying spring jamb of the shuttle door section. Where the intermediate door 27 is adjacent a door 28, forming part of the pivoted door unit, the abutment 61 shown at the right of Fig. 12 is unnecessary and should be omitted, since the pivoted doors do not depend on adjacent doors for the operation of their strip mechanism.

The actuating member 52 may be made of other shapes than the flat strip previously described. For example, in Fig. 19 the actuating member 52' is channel shaped, the open side being turned towards the rear wall 42 of the housing and the links 55 being pivoted to the web portion of the channel by the pins 56'. In this construction the springs 57' may be contained within the channel, one end being passed through two small holes in the upper or lower flange portion of the channel 52', while the other end is fastened to a pin 59' fixed in the rear wall 42 of the housing. The screws 44 which hold the housing in position at the lower edge of the door need not pass above the actuating member 52 or 52', but may, if desired, be seated in apertures 75 in the rear wall 42 of the housing between the actuating member and the base portion 45 of the door strip, registering apertures 76 being provided in the front wall 43 of the housing to permit insertion and tightening up of the screws when they are so located. This arrangement of the securing screws permits a somewhat narrower housing to be used, and thus makes the construction as a whole slightly more compact.

The invention has been thus far described as applied to a plurality of doors making up a folding partition, but in Figs. 20, 21 and 22 there is shown a modification adapted to be employed on a single swinging door, while in Fig. 23 another arrangement useful with a single swinging door is illustrated. In the first modification a roller 77 is journaled for vertical rotation in a bracket 78 which is permanently secured to the stationary jamb 79 at the free edge of the swinging door 80, the hinged edge of which is not illustrated. The construction of the door strip is identical with that shown on the shuttle door 38, but the yielding member 81 has the box-like housing 82 to protect the end of actuating bar 52 and prevent dirt from entering the end of the door strip housing. When the door is swung open, the actuating member 52 is moved to the left by its spring 57, not shown, so as to move the yielding member 81 to the dotted-line position shown in Fig. 20, thus lifting the

strip off the floor and permitting free swinging of the door. As the door is swung shut, roller 77 presses member 81 against the end of the actuating bar and moves it to the right 5 to bring the strip into contact with the floor or door sill as the door reaches its fully closed position.

In the modification shown in Fig. 23, an abutment 83 is made fast to the stationary 10 jamb 84 to which the door 85 is hinged by the hinge 86. The strip actuating member 52 carries a roller 87 which rides into contact with the concavely curved face of abutment 83 as the door swings shut, thus moving the bar 52 to the right and operating the door strip.

It is to be noted in all the constructions shown that there is no rubbing to wear out the parts as has been the case with certain 20 door strips heretofore known. Either the strips are operated by a straight thrust of an abutment against a longitudinally movable actuating bar, or as in the case of the swinging doors, the actuating bars are 25 moved in the direction of their length by means of some type of roller.

It is to be understood that the invention is not limited to the particular construction 30 of the illustrated embodiment of the invention but that the invention may be embodied in other forms within the scope of the claims.

What I claim as new is:

1. A folding partition comprising a 35 frame, a series of doors foldable in the frame into and out of the plane of the frame, certain of which doors are also mounted to slide in the frame in the plane thereof, a strip mounted on the lower edge 40 of each door and movable to close the space between the said edge and frame, means for maintaining said strips out of contact with the frame during folding and sliding movement of the doors, and automatic 45 means for operating the strips to close the spaces between the several doors and the frame when the doors are closed.

2. A folding partition comprising a 50 frame, a series of doors foldable in the frame into and out of the plane of the frame, certain of which doors are also mounted to slide in the frame in the plane thereof, a strip mounted on the lower edge 55 of each door and movable to close the space between the said edge and frame, means for maintaining said strips out of contact with the frame during folding and sliding movement of the doors, and operating 60 means carried by the frame and the several doors for operating said strips simultaneously to close said space when all of the doors are given their final closing movement to close the partition.

3. A folding partition comprising a

frame, a series of doors foldable in the 65 frame into and out of the plane of the frame, certain of which doors are also mounted to slide in the frame in the plane thereof, a strip mounted on the lower edge 70 of each door and movable to close the space between the said edge and frame, means for maintaining said strips out of contact with the frame during folding and sliding movement of the doors, and operating 75 means carried by the frame and the several doors for operating said strips simultaneously to close said space during the final operation in closing the partition.

4. A folding partition comprising a 80 frame, a series of door sections, certain of which are slidable in the frame in the plane thereof, the sections being made up of at least two doors hinged together at their meeting edges and mounted for folding movement with relation to the frame, a strip mounted on the lower edge of each 85 door and movable thereon to close the space between the said edge of the door and the frame, means for maintaining said strips in position out of contact with the frame 90 during folding movement of the doors and during sliding movement of the slidable sections, and means for operating simultaneously the door strips for all of the doors of the partition during the final closing of the partition.

5. A folding partition comprising a frame, a series of door sections, certain of which are slidable in the frame in the plane thereof, the sections being made up of at least 100 two doors hinged together at their meeting edges and mounted for folding movement with relation to the frame, a strip mounted on the lower edge of each door and movable thereon to close the space between the said 105 edge of the door and the frame, means for maintaining said strips in position out of contact with the frame during folding movement of the doors and during sliding movement of the slidable sections, means 110 on the frame for operating a strip on one of the end doors of the partition, and means on a door for operating the strip on an adjacent door.

6. A folding partition comprising a 115 frame, a series of door sections, certain of which are slidable in the frame in the plane thereof, the sections being made up of at least two doors hinged together at their meeting edges and mounted for folding 120 movement with relation to the frame, a strip mounted on the lower edge of each door and movable thereon to close the space between the said edge of the door and the frame, means for maintaining said strips 125 in position out of contact with the frame during folding movement of the doors and during sliding movement of the slidable

sections, and means having a toggle action for operating simultaneously the strips on a series of adjacent doors.

7. In door construction, a frame, a pair of doors hinged together at their meeting edges, and foldable with relation to the frame, strips movable to close the space between the lower edges of the doors and the frame, and means responsive to unfolding movement of said doors to operate said strips.

8. In door construction, a frame, a pair of doors having hinged meeting edges, one of the doors being pivoted to swing in the frame about another edge, strips carried at the lower edges of said doors to close the space between said edges and the frame, and having horizontally slidably members to move the strips to close the openings when the doors are relatively in the same plane within the frame.

9. A folding partition comprising a frame, a series of doors foldable in the frame into and out of the plane of the frame, certain of which doors are mounted to slide in the frame in the plane of the frame, and a pair of which doors in unfolding to close the partition have a toggle action, a strip mounted on the lower edge of each door to close the space between said edge and the frame, means for normally maintaining said strips in position out of contact with the frame, and means operated by the said toggle action of a pair of the doors for simultaneously operating all of the strips for the several doors to close the spaces between the same and the frame.

10. A folding partition comprising a frame, a series of doors foldable in the frame into and out of the plane of the frame, certain of which doors are also mounted to slide in the frame in the plane thereof, a strip mounted on the lower edge of each door and movable to close the space between the said edge and frame, means for maintaining said strips out of contact with the frame during folding and sliding movement of the doors, and means on each door for operating the strip on an adjacent door as the doors are moved into positions to close the partition.

11. A folding partition comprising a frame, a series of doors foldable in the frame into and out of the plane of the frame, certain of which doors are also mounted to slide in the frame in the plane thereof, a strip mounted on the lower edge of each door and movable to close the space between the said edge and frame, means for maintaining said strips out of contact with the frame during sliding and folding movement of the doors, means on one of the end doors of the partition for actuating the strip on said door, means on the frame for

operating said actuating means, and actuating means for the strips on other doors operated from the actuating means on the end door.

12. A folding partition comprising a frame, doors hinged together at their meeting edges and foldable with relation to the frame, a strip mounted on each of the doors to close the space between the doors and frame, means for maintaining the strips in position out of contact with the frame during folding movement of the doors, and means on each door for actuating the strip for said door arranged to be operated by the actuating means on an adjacent door.

13. In door construction, a frame, a sliding door therein comprising vertical jamb sections and a shuttle door section hinged to one of said jamb sections, strips movable to close the space between the lower edges of the sections and the frame, means on each section for actuating its own strip, the actuating means on one of the jamb sections cooperating when in operated position with the actuating means on the shuttle door when closing to operate the shuttle door strip, but said shuttle door strip actuating means being unaffected by said jamb strip actuating means when the latter are in normal position.

14. In door construction, a frame, a sliding door therein comprising jamb sections and a shuttle door hinged to one of the jamb sections, strips movable to close the space between the lower edges of the sections and the frame, a horizontally movable actuating member approximately coextensive with one jamb and adapted upon longitudinal movement to close the strip on said jamb section, a horizontally movable actuating member on the door section adapted upon longitudinal movement to close the strip on said door section, said jamb strip actuating member when operated serving as an abutment to move the door strip actuating member when the door is closed against the jamb, and means for moving said jamb strip actuating member at the end of travel of the sliding door.

15. A folding partition comprising a frame, doors hinged together at their meeting edges and foldable with relation to the frame, a strip mounted on each door to close the space between the door and the frame, means for maintaining said strips in position out of contact with the frame during folding movement of the doors, means on each door for actuating the strip for said door to engage the strip with the frame, the actuating means on at least one of the doors being arranged to be operated by the actuating means on an adjacent door.

16. A folding partition comprising a frame, a series of door sections, certain of

which are slidable in the frame in the plane thereof, the sections being made up of at least two doors hinged together at their meeting edges and mounted for folding movement with relation to the frame, a strip mounted on the lower edge of each door and movable thereon to close the space between the said edge of the door and the frame, means for maintaining said strips in position out of contact with the frame during folding movement of the doors and during sliding movement of the sections, and means for operating simultaneously the door strips for all of the doors of the partition during the final closing of the partition, the actuating means on the doors of each section being located wholly within the margins of said sections.

17. A folding partition comprising a frame, a series of doors foldable in the frame into and out of the plane of the frame, certain of which doors are mounted to slide in the frame in the plane thereof, a strip mounted on the lower edge of each door to close the space between said edge and the frame, means for maintaining said strips out of contact with the frame during sliding and folding movement of the doors, and means for simultaneously moving all the strips for the several doors of the partition to closed positions in response to closing of all of the doors.

18. A folding partition comprising a frame, a series of doors foldable in the frame into and out of the plane of the frame, certain of which doors are mounted to slide in the frame in the plane thereof, a vertically movable strip movably mounted on each door to close the space between the lower edge of the door and the frame, a member guided for horizontal movement to actuate each strip to close the same, and means acting on said members to hold the strips in elevated position during folding and sliding movement of the doors, the actuating members for certain of the doors being arranged to be operated by the actuating members of adjacent doors.

19. A folding partition comprising a series of movable main doors, a shuttle door, means for closing the space between the doors and frame comprising a strip mounted on the shuttle door, means for moving said strip to close the space between the shuttle door and the frame when the main door and the shuttle door are closed, and for moving the strip out of engagement with the frame when the shuttle door is opened.

20. A folding partition comprising a frame, a series of main doors movably mounted in the frame, a shuttle door movably mounted on one of the main doors, means for closing the space between the doors and the frame comprising a strip

mounted on the shuttle door, means for maintaining the strip out of contact with the frame when either the main doors or the shuttle door are open, and means for actuating the strip to close the same when both main doors and the shuttle door are closed.

21. A folding partition comprising a frame, a series of main doors movably mounted in the frame, a shuttle door mounted on one of the main doors, means for closing the space between the doors and the frame comprising a strip mounted on the shuttle door, and means for actuating the strip to move the same into engagement with the frame when the main door is closed and to move the same out of engagement with the frame when the main door is open.

22. A folding partition comprising a frame, a main door movably mounted in the frame and having jamb sections, a shuttle door mounted on the main door and engaging said jamb sections, strips mounted respectively on said jamb sections and on said shuttle door for closing the space between the same and the frame, and means for simultaneously actuating the strip on the shuttle door and the strips on the jamb sections when the main door is closed.

23. A folding partition comprising a frame, a main door movably mounted in the frame and having jamb sections, a shuttle door mounted on the main door and engaging said jamb sections, strips mounted respectively on said jamb sections and on said shuttle door for closing the space between the same and the frame, strip actuating means on the jamb sections, and strip actuating means on the shuttle door arranged to be operated from the strip actuating means on one of the jamb sections.

24. A folding partition comprising a frame, a main door movably mounted in the frame having jamb sections, a shuttle door mounted on the main door and engaging said jamb sections, strips mounted respectively on said jamb sections and on said shuttle door for closing the space between the same and the frame, and means for simultaneously moving the strip on the shuttle door and the strips on the jamb sections into engagement with the frame when the main door is closed and for moving the strip on the shuttle door out of engagement with the frame when the shuttle door is opened.

25. A folding partition comprising a frame, a main door movably mounted in the frame having jamb sections, a shuttle door mounted on the main door and engaging said jamb sections, strips mounted respectively on said jamb sections and on said shuttle door for closing the space between the same and the frame, strip actuating means on the jamb sections, and strip actuating means on the shuttle door arranged to be operated from the strip actuating

means on one of the jamb sections and arranged to be released by the latter actuating means to allow the shuttle door strip to be moved out of engagement with the frame 5 when the shuttle door is opened.

26. A folding partition comprising a frame, a series of doors foldable in the frame, certain of which doors are mounted

to slide in the frame in the plane thereof, and means carried by the several doors to close the openings between the doors and the frame when one of the doors is pressed against a side of the frame. 10

Signed at New York city, New York, this 11th day of December, 1923.

ARTHUR H. DODGE.
